United States Patent

Des. 241,311

Patented Sept. 7, 1976

241,311

SIGN HOLDER OR THE LIKE

David L. McLintock, Jacksonville, Fla., and Duff Porter III, Portsmouth, Va., assignors to Simple Signman Systems, Inc., Jacksonville, Fla.

Filed June 2, 1975, Ser. No. 583,417

Term of patent 14 years

Int. Cl. D8—08

U.S. Cl. D8—245

FIG. 1

FIG. 2

FIG. 3

FIG. 4

FIG. 5

FIG. 1 is a top perspective view of a sign holder or the like showing our new design;

FIG. 2 is a top view thereof;

FIG. 3 is a bottom view thereof;

FIG. 4 is an end elevational view thereof; and

FIG. 5 is an elevational view taken from one side thereof.

We claim:

The ornamental design for a sign holder or the like, substantially as shown.
